SIDEWALK SCOOTER

Johnnie D. Taylor, 3040 Park Ave. S.,
Minneapolis, Minn. 55407

Filed June 3, 1971, Ser. No. 149,878

Term of patent 14 years

Int. Cl. D12—99

U.S. Cl. D34—15

FIG. 1 is a left side elevational view of a sidewalk scooter showing my new design, the right side being a mirror image thereof;

FIG. 2 is a top plan view thereof;

FIG. 3 is a bottom plan view thereof;

FIG. 4 is a front elevational view thereof;

FIG. 5 is a rear elevational view thereof.

I claim:

The ornamental design for a sidewalk scooter, as shown and described.
